UNITED STATES PATENT OFFICE.

ALBERT CLEMENS, OF LOUISVILLE, KENTUCKY.

VANITY CASE.

Application filed November 4, 1925. Serial No. 66,793.

The present invention relates to vanity cases or powder boxes and puffs.

An object of the invention is to provide a case in which the puff is wholly concealed within the case and in contact with the powder when not in use for application of the powder, and in which the direct supporting means for the puff provides a closure for the opening through which the puff moves into and out of the case, when the puff is in the case.

Another object of the invention is to provide a case from which the puff can readily be detached for cleaning or renewal or for replenishing the supply of powder in the case.

Another object is to provide a vanity case wherein the necessity for touching the puff with the fingers during the movement of the puff into and out of the case is eliminated.

Another object of the invention is to provide an improved powder puff for a case of the type referred to, and an improved carrier and mounting means therefor.

Another object of the invention is to provide a case of the character referred to which can be economically manufactured and which is nevertheless attractive and serviceable.

Other objects and advantages will appear upon a fuller understanding of the construction and its operation.

The vanity case will be further described with reference to the accompanying drawing in which a preferred embodiment is shown and wherein:—

Fig. 1 is a side view of the case, the puff being projected for use;

Fig. 2 is a similar view except that the puff is shown but partly projected;

Fig. 3 shows a transverse section of the case at right angle to the view of Fig. 1, the puff being however wholly within the case;

Fig. 4 is a longitudinal sectional view of the case, showing the puff partly in elevation, and

Fig. 5 is a perspective view, somewhat enlarged, of one half of the carrier or core of the puff and the means whereby the puff is mounted on the case proper.

In the drawing the case comprises a hollow body portion 1, a puff 2 and a pivot 3 whereby the puff is rotatably mounted on the case. As shown, the body of the case

is rectangular in longitudinal section and may be formed by securing together along their rim portions two frusto-pyramidal pans or shells, preferably of metal, the bottoms of the pans forming the side faces of the case which may be suitably polished and otherwise decorated. At the junction of the rims the case may be provided, except along the top edge, with a bead 4.

The body 1 is closed along three of its edges and the fourth edge, shown at the top in the drawing, is closed over one-half of its length by a flat plate 5 suitably secured to the adjacent walls of the body. The remainder of the top edge is open and through this opening 6 the puff 2 is moved into and out of the casing. The pivot 3 is secured crosswise the plate 5 at its end next to the opening 6 and may be carried in an upwardly rolled flange 7 on the plate 5.

A plate 8 of about the same length as plate 5 turns by means of ears 9 on the pivot 3 and serves as a direct supporting means for the puff and also to close the opening 6 when the puff has been folded into the case. The plate 8 is provided at its end remote from the pivot 3 with a spring finger 10 which facilitates movement of the puff into and out of the case without the necessity of touching the puff with the fingers of the user. The outside of the spring finger 10 may be formed with a small dimple 11 and thus provide a latch through co-operation of the dimple 11 with a small boss 12 on a collar or flange 13 secured to the body 1 inside the opening 6.

Referring to Fig. 5, it will be seen that plate 8 is provided with staggered flanges 14, 15 on opposite sides of the plate, inwardly turned and each extending about one-half the length of the plate. These are part of my novel means for providing for ready attachment and detachment of the puff. The latter comprises a padded frame or core 16 of sheet metal or other thin and flexible material which may be a disk-segment in shape, although other forms may of course be adopted, and shown herein as a semi-circular disk. Portions may be cut out as indicated at 17 for economy of material and lightness and to facilitate attachment of the soft covering. This soft material, which is designated 18 in the drawing, may be of any suitable material well known in the art and has the form of a semi-circular disk in general, although,

as shown, it preferably extends over an arc somewhat greater than one hundred eighty degrees to insure closing of the opening 6 by its trailing radial face 19 when the puff is fully projected for use as indicated in Fig. 1. The puff is of sufficient thickness to entirely close the opening 6 as it passes through the same, so as to seal the case against spilling of the powder, even when the puff is fully withdrawn.

One edge of the core of the puff is provided with two outwardly turned flanges 20, 21 cooperating respectively with flanges 14 and 15 on the plate 8 to hold the puff on the latter. The puff is attached to the plate 8 simply by sliding from left to right, Fig. 5, the flange 21 under flange 15 and flange 20 under flange 14. The puff can thus be readily detached for cleaning or renewal or for replenishing the supply of powder in the case through the opening 6.

The use of the device will be fully understood from the foregoing description. It is not essential that the powder case contain sufficient powder to contact with the puff when the case is at rest, as shown in Figs. 3 and 4, but it is advisable to avoid the use of a greater quantity of powder as difficulty may be experienced in forcing the puff through the powder in closing the case. When the case contains a relatively small quantity of powder, the slight shaking which is incident to the normal carrying of the case is usually sufficient to bring the powder in contact with the puff, but if not, the user may shake and/or invert the case before withdrawing the puff. Obviously many changes may be made without departing from the intended scope of the invention, the latter being limited only as appears from the appended claims.

I claim:—

1. A vanity case comprising a body adapted to hold powder and closed except along an edge, and a puff carrier pivotally secured to the body transversely of said edge and adapted to close an opening along the edge when the puff is moved into the body wherein the puff has the form of a segment of a disk of appreciable thickness and wherein a radial face of said puff closes the opening when the puff is projected for use.

2. A vanity case comprising a body adapted to hold powder and closed except along an edge, and a puff carrier pivotally secured to the body transversely of said edge and adapted to close an opening along the edge when the puff is moved into the body wherein the pivot is midway the length of the edge and the opening extends between said pivot and one end only.

3. A vanity case comprising a body adapted to hold powder and closed except along an edge, and a puff carrier pivotally secured to the body transversely of said edge and

adapted to close an opening along the edge when the puff is moved into the body wherein the pivot is midway the length of the edge and the opening extends between said pivot and one end only, and wherein the puff has the form of a segment of a disk of appreciable thickness and wherein a radial face of said puff closes the opening when the puff is projected for use.

4. A vanity case comprising a body adapted to hold powder and closed except along an edge, and a puff carrier pivotally secured to the body transversely of said edge and adapted to close an opening along the edge when the puff is moved into the body wherein the puff is readily detachable from the carrier for renewal or cleaning.

5. A vanity case comprising a body adapted to hold powder and closed except along an edge, and a puff carrier pivotally secured to the body transversely of said edge and adapted to close an opening along the edge when the puff is moved into the body wherein the end of the carrier remote from the pivot has a spring finger piece serving as a latch and also to facilitate movement of the puff.

6. A vanity case comprising a body adapted to hold powder and closed except along an edge, and a puff carrier pivotally secured to the body transversely of said edge and adapted to close an opening along the edge when the puff is moved into the body wherein the carrier comprises a plate having oppositely disposed, staggered flanges overlapping the same adapted to receive thereunder corresponding flanges carried by the puff.

7. A vanity case comprising a body adapted to hold powder and closed except along an edge, and a puff carrier pivotally secured to the body transversely of said edge and adapted to close an opening along the edge when the puff is moved into the body wherein the body comprises two pan-shaped members secured together along their rim portions, the bottoms of the pan-shaped members forming the sides of said body.

8. A vanity case comprising a body adapted to hold powder and closed except along an edge, and a puff carrier pivotally secured to the body transversely of said edge and adapted to close an opening along the edge when the puff is moved into the body wherein the body comprises two pan-shaped members secured together along their rim portions, the bottoms of the pan-shaped members forming the sides of said body, and wherein the puff has the form of a segment of a disk of appreciable thickness and wherein a radial face of said puff closes the opening when the puff is projected for use.

9. A vanity case comprising a body adapted to hold powder and closed except along an edge and a substantially semi-circular

puff pivoted at one end of an opening along the edge at the center of said puff, said puff being of such thickness as to close the opening against spilling of the powder.

10. A puff for use in a vanity case of the character described in claim 9 comprising a thin frame or core of flexible material of disk-segment form and a covering of soft

material extending over an arc slightly greater than one hundred eighty degrees, 10 said core having means for attachment to the case.

In testimony whereof, I affix my signature.

ALBERT CLEMENS.
